(57) **CLAIM**

The ornamental design for a bird feeder, as shown and described.

DESCRIPTION

FIG. 1 is a top perspective view of a bird feeder showing the new design in an expanded configuration;
FIG. 2 is a bottom perspective view thereof;
FIG. 3 is a top view thereof;
FIG. 4 is a bottom view thereof;
FIG. 5 is a side view thereof;
FIG. 6 is a top perspective view thereof showing the new design in a collapsed configuration;
FIG. 7 is a bottom perspective view thereof in the collapsed configuration;
FIG. 8 is a top view thereof in the collapsed configuration;
FIG. 9 is a bottom view thereof in the collapsed configuration; and,
FIG. 10 is a side view thereof in the collapsed configuration. The broken lines in the drawings illustrate portions of the bird feeder that form no part of the claimed design.
